UNITED STATES PATENT OFFICE.

LYMAN B. POPE AND MARTIN F. MANN, OF HAVERHILL, MASSACHUSETTS; SAID
MANN ASSIGNOR TO SAID POPE.

SHANK-SHAPING MACHINE.

Application filed September 29, 1925. Serial No. 59,329.

This invention relates to machines for finishing Louis and similar heels, and particularly for shaping the shank portion of such a heel, or that which extends forward from the breast of the heel toward or along the shank of the shoe. The invention has for its general object to provide a novel mechanism for shaping this portion of a heel blank, said mechanism having a novel mode 10 of operation which, generally speaking, consists in applying the shank portion of the heel blank to the working face of a shaping tool and determining the curvature of the shank by turning the heel blank about an axis exterior to the tool, as distinguished from the machines heretofore usually employed in which the curvature of the shank is determined by the shape or path of movement of the tool. The machine includes 15 means whereby the heel blanks may be accurately moved or swung past the shaping tool in the proper path or arc in accordance with the requirements, and preferably also means whereby said blanks will be automatically discharged from the machine after 20 the shaping operation, and is substantially universally adjustable to adapt the same for use in connection with heels of widely 25 different sizes and shapes.

The more particular objects of the invention will best be understood from the following description of a preferred embodiment thereof illustrated in the accompanying drawings. It will be understood, however, 30 that the particular construction described and shown has been chosen for illustrative purposes merely, and that the invention, as defined by the claims hereunto appended, may be otherwise embodied without departure from its spirit and scope.

In the drawings:

Fig. 1 is a top plan view of the machine, showing, partly in section, a heel blank in the jack or work holder prior to being turned into operative engagement with the shaping tool.

Fig. 2 is a similar view showing the work holder turned to bring the heel blank into operative engagement with the tool.

Fig. 3 is a side elevation of the work holder with its mounting and associated parts looking in the direction of the arrow in Fig. 1.

Fig. 4 is an end elevation looking from the right in Fig. 3.

Fig. 5 is a detail section taken on the line 5-5, Fig. 3.

Fig. 6 is a vertical section and Fig. 7 a front elevation of a heel blank.

Figs. 8, 9 and 10 are diagrammatic views illustrating the operation.

While, as will hereinafter appear, the present machine is adapted for use in connection with heels of a wide variety of forms, a typical heel of the type to which the invention is applicable is shown at A in Figs. 6 and 7. Said heel in its finished form is provided with a concave upper surface *a* adapted to engage and fit the heel seat of the shoe, a suitable shaped back or body portion *d*, a breast portion *b*, and a shank *c* which projects forwardly from the breast. In the finished heel the shank *c* joins the breast *b* and usually merges therewith in a smooth curve, as shown in Fig. 6, said shank being also transversely curved in accordance with the transverse curvature of the heel seat engaging portion *a*, as most clearly shown in Fig. 7. The heel seat engaging portion *a*, breast *b*, and back *d* are formed, prior to the transverse shaping of the shank *c*, by instrumentalities which constitute no portion of the present invention. The heel blank, after the operation of said instrumentalities, has a shank of the shape indicated by dotted lines in Figs. 6 and 7, the under side thereof adjacent the breast *b* being transversely straight as the result of the formation of said breast *b*, which gives said shank its proper vertical curvature but leaves, particularly at the sides of the shank, a quantity of surplus material *e* which is subsequently removed to finish the shank. It is to the subsequent shaping or finishing of the shank *c*, by removing this surplus material *e*, to give said shank its proper transverse curvature in parallelism to the heel seat engaging portion *a*, that the present invention relates.

Referring to Fig. 8, the shank shaping operation is performed by means of a shaping tool B which may be of any suitable type adapted to remove the surplus material *e* and the transverse configuration of whose working face (as hereinafter more fully explained) corresponds to the vertical curve in which the shank *c* merges into the breast *b*. In the embodiment of the invention shown, said tool comprises a grinding disk mounted to rotate about an axis X and

whose periphery P constitutes the working face. The heel blank A is swung past the working face of the tool B in an arc which is substantially tangential to said working face and whose axis is indicated at Y. The axis Y is eccentric to the axis X, is exterior to the tool B, and is located at the centre of transverse curvature of the heel seat engaging portion *a* of the blank, said blank being so 10 swung as to maintain this relationship between said surface and axis. The distance of the axis Y from the periphery of the tool B corresponds to the radius of curvature of said surface *a* plus the desired thickness, if 15 any, of the shank *c*. It will, therefore, be seen that as the blank A is so swung past the tool B from the position I shown in Fig. 8, through the position II, and into the position III, the originally straight under surface of the shank *c* will be shaped by the tool B into a transversely curved surface concentric to the surface *a*.

Mechanism by which the above results may be accomplished is illustrated in Figs. 1 25 to 5. As shown therein the tool B is suitably mounted on the end of a shaft 15 provided with a pulley 16 by which power may be applied from any suitable source through a belt 17. The shaft 15, whose axis is the 30 axis X of Fig. 8, is suitably journalled in a head 18 on a table 19. The heel blank A is carried in a jack or work holder, hereinafter described, which is eccentrically mounted on a shaft 20, whose axis is the axis Y of Fig. 35 8, said shaft being journalled in suitable bearings in a second head or mounting on the table 19 and being provided at its outer end with a hand wheel 21 by means of which it can be conveniently turned to 40 swing the heel blank A past the tool B, as above explained.

The work holder or jack comprises a supporting plate 22 having a pair of parallel, angularly disposed arms 23 adapted to be 45 clamped in adjusted position, with an interposed template 24, hereinafter described, between a fixed head or collar 5 and a washer 26 on the shaft 20, by means of a nut 27 on the threaded end of the latter. The supporting plate 22 carries a clamp by means of 50 which the heel blank A may be detachably secured thereto, said clamp comprising relatively fixed and movable clamping members 8 and 9. The fixing clamping member 8 comprises a dog pivoted at 3 to a slide 31 laterally adjustable on the plate 22 and secured in adjusted position thereon by a screw clamp 32. It will be seen that the 55 slide 31 may be laterally adjusted to accommodate heel blanks of different widths, the pivoted dog 8 adapting itself automatically to the shape of the blanks. The movable clamping member 9 comprising a dog pivoted at 4 to the plate 22 and having an extended end 2 connected by a spring 35 with

the offset end of an angular stud 36 angularly adjustable in the plate 22 to vary the tension of said spring, the movement of said dog under the influence of said spring being limited by an adjustable stop 37.

The head or mounting for the work holder 22 and shaft 20 comprises a support or carriage 38 adjustable in the direction of the axis of the shaft 20 by means of a manually operated adjusting screw 39 in a guide 40 70 on a second carriage 41. The carriage 41 is adjustable, in a direction transverse to the axis of the shaft 20, by means of a manually operated adjusting screw 42, on a guide 43 secured to the table 19 by means of a 75 clamp comprising a threaded stem 44 extending through an enlarged opening 45 in the table and provided on the underside of the latter with a threaded, hand operated nut 46. The opening 45, whose preferred 80 form is roughly that of a cross, as shown in dotted lines in Fig. 1, permits a substantially universal bodily, as well as an angular adjustment of the work supporting head 85 as a whole over the table 19.

The axes X and Y of the shafts 15 and 20 respectively preferably lie substantially in a common plane parallel to the table 19, and the adjustment last referred to permits variation of the position of the axis Y both 90 angularly and bodily with respect to the axis X in said plane. The adjustment of the carriage 41 on the guide 43 provides for adjustment of the axis Y, and consequently of the work holder 22, in a direction transverse 95 to said axis, while the adjustment of the carriage 38 in the guide 40 provides for adjustment of the work holder longitudinally of said axis, these adjustments being with 100 respect to the axis X and tool B.

In addition, the means, comprising the clamping nut 27, for securing the work holder 22 to the shaft 20 permits adjustment of said work holder relative to the shaft 20 in a direction transverse to the axis 110 of the latter. The template 24 is formed with a peripheral portion in the form of an arc of a circle whose radius corresponds to the radius of the transverse curvature of the heel seat engaging portion *a* of the heel blank A. Different templates 24 having peripheral surfaces corresponding to different 115 forms of heel blanks may be interchangeably employed, the detachable mounting of the template and work holder permitting the use of a template chosen in accordance with the particular form of heel blank to be operated upon. A template having the proper curvature having been put in place, the work holder 22 is clamped in such position, transversely of the shaft 20, as to permit the heel seat engaging portion of the blanks to be seated upon said periphery, thereby automatically determining the 120 radius of curvature of the shaped under surface 125 of the blank.

face of the shank and causing said surface to be accurately concentric with the surface *a*. The latter factor having been thus determined, the carriage 41 may be so adjusted on its guide 43 as to compensate for the adjustment of the work holder 22 on the shaft 20 and cause the proper engagement of the work with the tool B when said shaft is swung by means of the hand wheel 21. This adjustment determines the vertical thickness of the shank. Adjustment of the carriage 38 on the guide 40 in the direction of the axis of the shaft 20 varies the position of the work with respect to the tool in accordance with the length, from front to rear, of the shank with respect to the breast of the heel.

The bodily adjustments above referred to of the work carrying head over the table 19 permit the latter to be adjusted roughly in the two respects last referred to prior to the finer adjustment of the carriages 38 and 41 on the guides 40 and 43 by means of the adjusting screws 39 and 42. The angular adjustment of the work carrying head on the table 19 varies the angle between the axes X and Y and consequently the point of engagement of the work with the tool. As shown in Fig. 9, a tool B¹ having a periphery P¹ of variable curvature at different points may be employed. Thus, for example, the periphery P¹ of the tool B¹ may have a relatively sharp curvature, or a curvature of relatively short radius, at a point p¹ at its mid-portion and portions p² of relatively flatter curvature, or longer radius, at its sides. With such a tool, it will be seen that heels having shanks of different longitudinal curvature may be shaped by varying the angular relationship of the work with the tool and consequently the engagement of the former with the latter. Thus, a heel blank A¹ having a relatively short shank of relatively sharp curvature may be shaped by engagement with the portion p¹ of the working face P¹, or a heel blank A² having a shank of flatter curvature may be shaped by engagement with the portion p² of the working face P¹. It will be understood that the angular adjustment of the head may readily be compensated for in other respects by the other adjustments referred to.

Shaping tools having working faces or peripheries of different configurations may, of course, be employed interchangeably in accordance with the form of the work. Thus, in Fig. 10 is shown a tool B² having a flat or cylindrical working face P² for operation upon a heel A³ whose shank intersects its breast at an angle instead of merging therewith in a curve as in the other forms shown.

In order that the heel blanks A, when applied to the work holder, may be properly

positioned thereon in accordance with the other adjustments of the machine, as well as to square the breast of the heel with respect to the shaping tool and to fix the position of the shanks with reference to the template 24, a breast gauge 50 is preferably employed, said breast gauge being mounted for horizontal adjustment longitudinally of the axis of the shaft 20 upon a slide 51 which in turn is mounted for vertical adjustment in a direction transverse to said axis on the carriage 38. To this end the gauge 50 is preferably provided with a slot 52 to receive a clamping screw 53 for securing the same in adjusted position to the slide 51, while said slide 51 is formed with a slot 54 to receive an adjusting screw 55 by means of which said slide may be clamped in adjusted position to the carriage 38. The adjustment of the gauge 50 in the direction of the axis of the shaft 20 provides for heel blanks having shanks of different lengths, while the adjustment transverse to said axis is to compensate for transverse adjustment of the work holder in accordance with the size of the template 24, and also to permit said gauge to engage the breast of the heel blank at the most advantageous point.

The work engaging edge of the gauge 50 is straight and relatively long in order to permit the angular squaring of the breast of the heel blank when the latter is placed in position on the work holder, and in order to permit the swinging of the work holder from the upper, work-receiving position shown in Figs. 1, 3 and 4, and at I, in Fig. 8, past the tool, as shown in Fig. 2, and at II, in Fig. 8, without interference on the part of said gauge, it is desirable that the said work holder be moved in the direction of the axis of the shaft 20 a short distance to disengage the same from said gauge. To this end the shaft 20 is provided with a cam 56 which cooperates with a fixed cam 100 follower 57 on the carriage 38, so that as the work holder is turned out of its work receiving position the shaft 20 will move longitudinally toward the tool, and when said work holder is returned to said position said shaft will be moved longitudinally in the opposite direction to bring the work holder into proper position for cooperation with the gauge. In order further to fix the work-receiving position of the work holder, the shaft 20 is preferably formed with a shoulder 58 (Fig. 5), which cooperates with a spring-pressed pawl 59 in the carriage 38, said shoulder engaging said pawl when the work holder is turned into the work-receiving position in the direction of the arrow on said figure.

After the heel blank has been swung past the tool B to complete the shaping operation as shown at III in Fig. 8, the clamp is auto

matically opened to release and discharge said blank by means of a fixed cam member 60 carried by a bracket 61 projecting from the carriage 38, said cam member being engaged by the projecting end 2 of the movable member 9 of the clamp to retract the latter against the spring 35 when the position III is reached. While the cam member 60 is normally fixed, it is preferably adjustable longitudinally of the bracket 61 in order to secure the best cooperation thereof with the clamp, and to this end is provided with a clamping screw 62 which passes through a longitudinal slot 63 in said bracket.

Having thus described our invention, we claim:

1. In a heel shank shaping machine, in combination, a shaping tool, a template having a curved periphery to fit the heel seat engaging portion of a heel blank, a mounting for said template upon which it is adapted to turn about the axis of said periphery to swing the latter past said tool, and a work holder associated with said template for holding a heel blank with its heel seat engaging portion in engagement with said periphery.

2. In a heel shank shaping machine, in combination, a shaping tool, a template having a curved periphery to fit the heel seat engaging portion of a heel blank, a work holder for holding a heel blank with its heel seat engaging portion in engagement with said periphery, and a common mounting for said template and work holder upon which they may be swung about the axis of said periphery past said tool, said template being detachably carried by said mounting, and said work holder being adjustable thereon toward and from said axis to permit the use of templates having peripheries of different radii.

3. In a heel shank shaping machine, in combination, a shaping tool, a work holder, a mounting for said work holder upon which it may be swung in an arc past the working face of said tool, and means for automatically moving said work holder in the direction of the axis of said arc into and out of the plane of said working face as it is swung.

4. In a heel shank shaping machine, in combination, a shaping tool, a work holder, a shaft on which said work holder is eccentrically mounted, a mounting in which said shaft is journaled to swing said work holder past the working face of said tool, a cam on said shaft, and a fixed cam follower engaged by said cam to move said shaft in the direction of its axis when said shaft is turned.

5. In a heel shank shaping machine, in combination, a shaping tool, a work holder, and a mounting for said work holder upon which the latter is adapted to swing about a

normally fixed axis in an arc past said tool, said mounting being angularly adjustable to vary the position of said axis about said tool and consequently the engagement of a heel blank carried by said work holder with said tool.

6. In a heel shank shaping machine, in combination, a shaping tool having a working face of varying form at different portions thereof respectively, a work holder, and a mounting for said work holder upon which the latter is adapted to swing in an arc past said tool, said mounting being angularly adjustable to vary the position of the axis of said arc about said tool, thereby causing a heel blank carried by said work holder to engage different portions of said working face.

7. In a heel shank shaping machine, in combination, a table, a head thereon, a shaping tool carried by said head, a second head on said table, and a work holder mounted in said second head to swing past said tool, one of said heads being adjustable on said table to vary the path of movement of said work holder with respect to said tool.

8. In a heel shank shaping machine, in combination, a table a head thereon, a shaping tool carried by said head, a second head on said table, and a work holder mounted in said second head to swing past said tool, one of said heads being bodily movable over said table and attachable thereto in a variety of positions to vary the path of movement of said work holder with respect to said tool.

9. In a heel shank shaping machine, in combination, a table having an enlarged opening therein, a head on said table, a shaping tool carried by said head, a second head on said table, a work holder mounted in said second head to swing past said tool, one of said heads having a shank, and said table having an enlarged opening through which said shank passes, and clamping means cooperating with said shank to secure said last named head in adjusted position to said table.

10. In a heel shank shaping machine, in combination, a shaping tool having a working face shaped to conform to the desired shape of the shank in one direction, a work holder, a mounting for said work holder upon which it may be swung in an arc past the working face of said tool, said mounting being adjustable in the direction of the axis of said arc to vary the point of engagement of said tool with a heel blank carried by said work holder, and means for securing a heel blank to said work holder with its shank portion extending in a direction parallel to said axis.

11. In a heel shank shaping machine, in combination, a table, a shaping tool, means on said table for supporting said tool, a work holder, a support on which said work holder

- is mounted to swing in an arc past the working face of said tool, means for securing a heel blank to said work holder with its shank portion extending in a direction parallel to the axis of said arc and a guide on said table on which said support is adjustable in the direction of said axes.
12. In a heel shank shaping machine, in combination, a shaping tool having a working face shaped to conform to the desired shape of the shank in one direction, a work holder, a mounting for said work holder upon which it may be swung in an arc past the working face of said tool, said mounting being adjustable in the direction of the axis of said arc and also in a direction transverse to said axis to vary the point of engagement of said tool with a heel blank carried by said work holder, and means for securing a heel blank to said work holder with its shank portion extending in a direction parallel to said axis.
13. In a heel shank shaping machine, in combination, a shaping tool having a working face shaped in cross section to conform to the desired shape of the shank in one direction, a work holder, a mounting for said work holder upon which it may be swung in an arc past the working face of said tool, said work holder being adjustable on said mounting toward and from the axis of said arc, and said mounting being also adjustable in a direction transverse to the axis of said arc, and means for securing a heel blank to said work holder with its shank portion extending in a direction parallel to said axis.
14. In a heel shank shaping machine, in combination, a table, a shaping tool thereon, a work holder, and a mounting for said work holder upon which it may be swung in an arc past the working face of said tool, said mounting including a member secured to said table and universally adjustable thereover and a member by which said work holder is carried, said last named member being adjustable on said first named member in the direction of the axis of said arc and also in a direction transverse to said axis.
15. In a heel shank shaping machine, in combination, a table, a shaping tool, means on said table for supporting said tool, a work holder, a support on which said work holder is mounted to swing in an arc past the working face of said tool, a carriage having a guide on which said support is adjustable, and a guide on said table on which said carriage is adjustable, one of said adjustments being in the direction of and the other in a direction transverse to said axis.
16. In a heel shank shaping machine, in combination, a table having an enlarged opening therein, a shaping tool, means on said table for supporting said tool, a work holder, a support on which said work holder is mounted to swing in an arc past the working face of said tool, a carriage having a guide on which said support is adjustable, and a guide on said table on which said carriage is adjustable, one of said adjustments being in the direction of and the other in a direction transverse to said axis.
17. In a heel shank shaping machine, in combination, a shaping tool, a work holder mounted to swing past said tool, and a fixed gauge for positioning a heel blank on said work holder prior to the movement of the latter to present said blank to said tool, and means whereby said movement carries said blank out of engagement with said gauge and into engagement with said tool.
18. In a heel shank shaping machine, in combination, a shaping tool, a work holder mounted to swing in an arc past the working face of said tool, a fixed gauge for positioning a heel blank on said work holder prior to the movement of the latter to present said blank to said tool, and means for moving said work holder in the direction of the axis of said arc as it is swung to carry said blank away from said gauge and into the plane of the working face of said tool.
19. In a heel shank shaping machine, in combination, a shaping tool, a work holder mounted to swing about an axis past said tool, a gauge for positioning a heel blank on said work holder prior to the movement of the latter to present said blank to said tool, and means whereby said movement carries said blank out of engagement with said gauge and into engagement with said tool, said gauge being normally fixed but being adjustable in the direction of said axis.
20. In a heel shank shaping machine, in combination, a shaping tool, a work holder mounted to swing about an axis past said tool, a gauge for positioning a heel blank on said work holder prior to the movement of the latter to present said blank to said tool, and means whereby said movement carries said blank out of engagement with said gauge and into engagement with said tool, said gauge being normally fixed but being adjustable in a direction transverse to said axis.
21. In a heel shank shaping machine, in combination, a shaping tool, a work holder, a mounting for said work holder upon which it may be swung in an arc past the working face of said tool, and a gauge for positioning a heel blank on said work holder prior to the movement of the latter to present said blank to said tool, said mounting being adjustable in the direction of the axis of said arc, and said gauge being normally fixed but being also adjustable in the direction of said axis.
22. In a heel shank shaping machine, in combination, a shaping tool, a work holder,

- a mounting for said work holder upon which the latter is adapted to swing in an arc past said tool and upon which it is adjustable toward and from the axis of said arc, and a 5 gauge for positioning a heel blank on said work holder prior to the movement of the latter to present said blank to said tool, said gauge being normally fixed but being adjustable in a direction transverse to said 10 axis.
23. In a heel shank shaping machine, in combination, a shaping tool, a work holder mounted to swing past said tool, and a clamp on said work holder for securing a heel blank thereto, said clamp including a laterally adjustable slide having a pivoted blank 15 engaging member and a cooperating spring pressed member for forcing the blank against said first named member.
24. In a heel shank shaping machine, in combination, a shaping tool, a work holder mounted to swing past said tool, a clamp on said work holder for securing a heel blank thereto, and means for opening said clamp 20 to release said blank when the latter has been moved past said tool.
25. In a heel shank shaping machine, in combination, a shaping tool, a work holder mounted to swing past said tool, a clamp on said work holder for securing a heel blank thereto, said clamp including a spring 25 pressed member, and means for retracting said member to release said blank when the latter has been moved past said tool.
26. In a heel shank shaping machine, in combination, a shaping tool, a work holder mounted to swing past said tool, a clamp on said work holder for securing a heel blank thereto, said clamp including a spring 30 pressed member, and a fixed cam engaged by said member to retract the same and release said blank when the latter has been moved past said tool.
27. In a heel shank shaping machine, in combination, a shaping tool, a work holder mounted to swing past said tool, a clamp on said work holder for securing a heel blank thereto, said clamp including a spring 35 pressed member, and a fixed cam engaged by and retracting said member to release 40 said blank when the latter has been moved past said tool.
28. In a heel shank shaping machine, in combination, a shaping tool having a working face of varying form at different portions thereof respectively, a work holder, and a mounting for said work holder upon which the latter is adapted to swing in an arc past said tool, said mounting being angularly adjustable to shift the position of the 45 axis of said arc bodily about said tool, thereby causing a heel blank carried by said work holder to engage different portions of said working face.

In testimony whereof we affix our signatures.

LYMAN B. POPE.
MARTIN F. MANN.
